CLAIM

The ornamental design of a personal portable bidet, as shown.

DESCRIPTION

FIG. 1 is a top plan view of a personal portable bidet unit for a toilet showing my new design;

FIG. 2 is a left side elevational view thereof;

FIG. 3 is a front elevational view thereof;

FIG. 4 is a rear elevational view thereof;

FIG. 5 is a bottom plan view thereof; and,

FIG. 6 is a left side elevational view thereof.

The broken line representation of a toilet and an toilet seat cover in FIGS. 1, 2, and 6 are for purposes of illustration only and form no part of the claimed design.
